3 Claims. (Cl. 179—171)

My invention relates to amplifiers which have an input transformer for matching the input impedance of the amplifier to the supply, or an output transformer for matching the output impedance of the amplifier to the load, or which have both of such transformers.

Such matching of transformers is necessary, for instance, in line amplifiers in telephony circuits to avoid undesirable reflection phenomena between the amplifier and the transmission lines connected thereto. The input impedance and output impedance of the line amplifier, as well as the impedance of the transmission lines, may be considered as approximately ohmic resistances so that matching is obtained if the transformation ratio of each of these corresponds to the square root of the ratio of the resistances to be matched. In this case the impedance of the amplifier as measured between the terminals of the primary winding of the input transformer, or between the terminals of the secondary winding of the output transformer, constitutes an ohmic resistance corresponding to the impedance of the transmission line connected thereto. However, this holds good only for those frequencies at which the leakage inductance and the winding capacities of the transformer may be neglected. At higher frequencies the input and output impedances of the amplifier can no longer be considered as ohmic.

The main object of my invention is to provide means by which the influence of the leakage-inductance and of the winding capacity of the input transformer or the output transformer, or both transformers of amplifiers, can be removed in the frequency-range to be transmitted, so that in this frequency-range the input impedance or output impedance or both impedances of the amplifier always conserves an ohmic character.

In accordance with the invention I obtain the above object by so proportioning the capacities located in parallel with the winding of the input transformer, the output transformer or both transformers, that these capacities and the leakage self-inductance of each transformer constitute a low-pass filter of the π -type whose cut-off frequency corresponds at least to the highest frequency to be amplified.

As is well known, a low-pass filter of the π -type has an image impedance in the transmission range which is an ohmic resistance. This resistance is substantially constant in a considerable part of that range, but increases in the vicinity of the cut-off frequency. To achieve correct matching in the frequency-range to be amplified

5 the low-pass filter constituted by the input transformer or output transformer is, according to a further feature of the invention, proportioned that the cut-off frequency is higher than the highest frequency to be amplified by the amplifier, with the result that the frequency-range to be amplified coincides with that part of the transmission band of the low-pass filter in which the image impedance, under the conditions to be satisfied, can be considered as constant.

10 An amplifier which has an output transformer transformed in the above manner into a low-pass filter is particularly useful in connection with a negative feed-back by which, as is well known, non-linear distortion in the amplifier can be avoided. When, in a degeneratively back-coupled amplifier, the negative feed-back voltage is taken from the output circuit of an amplifier comprising an output transformer, phase displacements occur at the higher frequencies to be amplified due to the leakage inductance and the winding capacity of the output transformer. This phase displacement may attain such a high value that the negative feed-back passes into 15 back-coupling which may cause self-oscillation of the amplifier. At the same time the value of the negative feed-back will vary also at the higher frequencies. When utilizing negative feed-back of the output circuit of an amplifier comprising an output transformer transformed into 20 a low pass filter, and assuming the amplifier load to be substantially resistive, both the phase and the value of the negative feed-back remain substantially constant through the entire frequency 25 range to be amplified so that there is no danger of self-oscillation of the amplifier in this range. As regards frequencies exceeding the limiting frequency of the low-pass filter, the phase of the negative feed-back will of course vary, but also 30 at this frequency there is no danger of self-oscillation, because the attenuation of the low-pass filter beyond the range of transmission increases and hence the value of the back-coupled voltage 35 decreases very rapidly.

40 In order that the invention may be clearly understood and readily carried into effect, I shall describe the same in more detail with reference to the accompanying drawings, in which:

45 Figure 1 is a schematic diagram of a line amplifier.

Fig. 2 is a schematic diagram of the line amplifier of Fig. 1 with equivalent circuits shown for the transformers.

Fig. 3 is a schematic diagram of the line am-

plifier of Fig. 1 with equivalent circuits of the transformers at the higher frequencies,

Fig. 4 is a graph showing the relationship between image impedance and frequency.

Fig. 5 is a schematic diagram of an amplifier with negative feed-back and embodying the invention,

Fig. 6 is a schematic diagram of an output circuit of an amplifier according to the invention,

Fig. 7 is a schematic diagram of an output circuit of an amplifier according to the invention and combining voltage feed-back and current feed-back,

Fig. 8 is an equivalent circuit for the amplifier of Fig. 7, and

Fig. 9 is a phase diagram of the circuit of Fig. 8.

The line amplifier shown in Figure 1 is connected between two transmission lines 4 and 6 and comprises a first amplifying tube 1 and an output tube 2 which has an internal resistance R_2 . One or more amplifying tubes (indicated by the reference numeral 50) may be connected between the amplifying stages represented by tubes 1 and 2. The amplifying tube 1 has an input circuit including an input transformer 3, which has a transformation ratio $1:n_1$, of such a value that the grid-cathode impedance of the tube 1, which is determined by a resistance R_1 , is matched to the impedance of transmission line 4 whose impedance may be represented approximately by an ohmic resistance R .

As the resistances R_1 and R_2 are large relatively to the line impedance R , the input transformer 3 has to step up and the output transformer 5 has to step down. Owing to their large number of turns the secondary winding of the input transformer 3 and the primary winding of the output transformer 5 have self-capacities which cannot be neglected. Moreover, the grid-cathode capacity and anode-cathode capacity respectively of the amplifying tubes 1 and 2 respectively is connected in parallel with them. In Figure 1 the sum of these capacities are designated in dotted lines by condensers C_1 and C_2 .

According to the invention condensers having values of C_1/n_1^2 and C_2/n_2^2 are connected in parallel with the primary winding of the input transformer and in parallel with the secondary winding of the output transformer respectively.

As will appear from the following discussion, the input transformer 3 and the output transformer 5 are thus transformed into low-pass filters. When the input and output-transformers of the circuit shown in Fig. 1 are replaced by the equivalent circuit well known for transformers a circuit such as shown in Fig. 2 is obtained. In Fig. 2 the reference letters L_1 and L_2 represent the primary leakage inductance and the secondary leakage inductance respectively, M_1 represents the mutual inductance and n_1 the transformation ratio of the input transformer 3. The reference letters L_3 and L_4 indicate the primary leakage inductance and the secondary leakage inductance respectively, M_2 indicates the mutual inductance and n_2 indicates the transformation ratio of the output transformer 5.

From the diagram shown in Fig. 2 it appears that at high frequencies the inductances L_1 , L_2 and L_3 and L_4 , as well as the winding capacities C_1 and C_2 have an influence and that at such frequencies the input impedance and output impedance of the amplifier are no longer determined exclusively by the resistances R_1 and R_2 . At high frequencies the impedance of the mutual inductances M_1 and M_2 has such a high value that they

are negligible so that the diagram shown in Fig. 2 can be replaced by the diagram shown in Fig. 3 in which $L' = n_1^2 L_1 + L_2$ and $L'' = L_3 + n_2^2 L_4$. As shown in Fig. 1, a condenser

$$\frac{C_1}{n_1^2}$$

is connected in parallel with the primary winding of the input-transformer 3, a capacity C_1 is located between the input-terminals E_1 and E_2 in the diagram shown in Fig. 3 so that a low-pass-filter ensues. The leakage inductances L_1 and L_2 and the secondary winding capacity C_1 , (which can be increased at will by the parallel-connection of a condenser) are proportioned so as to satisfy the relation:

$$R^2 = \frac{L'}{2C}$$

In this case the image impedance Z_r of the low-pass filter may be represented by the expression:

$$Z = \frac{R}{\sqrt{1 - \left(\frac{f}{f_0}\right)^2}}$$

25 in which f represents the frequency and f_0 equals

$$\frac{1}{2\pi RC_1}$$

and represents the cut-off frequency. R is the nominal value of the image impedance which corresponds to the impedance of the transmission line 4.

Fig. 4 shows the image impedance Z_r as a function of the frequency f , and from the curve thereon it appears that the image impedance, in a very broad frequency-range below the cut-off frequency f_0 , is approximately constant with a nominal value R and then increases with the frequency. When selecting a cut-off frequency f_0 which is higher than the highest frequency to be amplified by the amplifier in such manner that the frequency-range to be amplified coincides with the frequency-range in which the image impedance of the low-pass filter may be considered to be substantially constant, it is possible to obtain a sufficiently exact matching of the input-impedance of the amplifier to the transmission line 4 in the frequency-range to be amplified and consequently reflection phenomena are avoided.

50 In exactly the above manner a condenser

$$\frac{C_2}{n_2^2}$$

can be connected in parallel with the secondary winding of the output transformer 5 so that a capacity C_2 lies between the output terminals U_1 and U_2 in the diagram shown in Fig. 3, and that a low-pass filter is formed also in the output circuit of the amplifier. This filter is likewise proportioned so that the output impedance of the amplifier in the frequency range to be amplified is matched to the impedance R of the transmission line 6.

65 After transforming the output transformer of an amplifier into a low-pass filter in the above manner the use of negative feedback extending from the output circuit to the input circuit of a preceding amplifying tube has special advantages. This will be pointed out with reference to Fig. 5 which shows an amplifier with voltage feedback and comprises two stages including amplifying tubes 1 and 2 interconnected by a network 7. The primary winding of the input transformer 3 and the secondary winding of the output transformer 5 are shunted by condensers C_1 and C_2 respectively,

so that they are transformed into low-pass filters, and the input impedance and output impedance of the amplifier are matched to the impedance of the transmission line 4 and 6 respectively. Voltage feedback of the output circuit of the amplifying tube 2 on to the input-circuit of the amplifying tube 1 is achieved by means of a third winding 8 of the output-transformer 5, which winding is connected in the grid circuit of the tube 1. As has been set forth above, the impedance, measured between the primary terminals of the output-transformer in the frequency-range to be amplified, is a constant resistance, and therefore the value and phase of the degeneratively back-coupled voltage across the winding 8 and the output-transformer are also constant. Consequently, undesirable phase-displacements of the voltage fed back cannot occur in the frequency-range to be amplified.

For frequencies exceeding the cut-off frequency of the low-pass filter, the impedance measured between the primary terminals of the output transformer is capacitative. Consequently the phase-angle between the voltage induced in winding 8 and the voltage to be amplified and supplied to tube 1 decreases with increasing frequency with the result that the negative feedback can pass into a back-coupling at sufficiently high frequencies. However, from the curve shown in Fig. 4 it appears that the value of the impedance Z_π , and consequently also the voltage between the primary terminals of the output transformer 5, rapidly decreases above the cut-off frequency of the low-pass filter, so that the stated decrease of the phase angle results in a decrease in value of the generatively back-coupled voltage. Consequently, for frequencies which are so high that back-coupling instead of negative feedback occurs, self-oscillation of the amplifier cannot occur in spite thereof, because the back-coupled voltage is too small at these frequencies.

In some cases it may be desirable that the amplitude of the back-coupled voltage induced in the winding 8 be maintained constant in the entire transmission band of the low-pass filter constituted by the output-transformer. This can be ensured by giving the capacity connected in parallel with the primary winding a larger value, preferably equal to $2C_2$. In this case the output-circuit of the amplifying tube 2 is connected in the manner shown in Fig. 6 in which the same reference characters are used to indicate the same parts of Fig. 5.

The impedance Z measured between the primary terminals of the output-transformer 5 is now constituted by the image impedance Z_π and the impedance of a condenser C_2 connected in parallel therewith.

$$\frac{Z_\pi}{1+j\omega C_2 Z_\pi}$$

The absolute value of Z , i. e. $|Z|$, equals:

$$\frac{R}{\sqrt{1 - \frac{f^2}{f_{c2}^2} + (2\pi f)^2 R^2 C_2^2}}$$

As

$$f_c = \frac{1}{2\pi R C_2}$$

substitution of this value in the above term gives the following:

$$|Z| = R$$

Consequently the absolute value of the impedance Z is constant in the entire transmission range. In this case there is set up across the

primary winding in the transmission range a constant voltage which induces a voltage which is also constant. In this case the degenerative back-coupling always retains the same value.

The voltage feedback may advantageously be combined with a current feedback, and this will be explained with reference to Fig. 7. In circuit shown in this figure the negative feedback consists of two components i. e. a voltage which is set up across the winding 8 and depends on the voltage set up across the primary winding of the output transformer 4, and a voltage which is set up across the resistance 9 and depends on the current traversing the primary winding.

The phase-variations of the entire degeneratively back-coupled voltage with respect to frequencies lying outside the frequency-range are such that the negative feed-back never can pass into a back-coupling, as will be appreciated from the equivalent circuit shown in Fig. 8 and the corresponding phase-diagram shown in Fig. 9.

In the equivalent circuit of Fig. 8 the amplifying tube 2 is replaced by a source of E. M. F., shown as a generator e , and an internal resistance R_2 . The impedance measured between the terminals of the primary winding of the output-transformer is represented by the image impedance Z_π of the low-pass filter. For simplicity it is assumed that the voltage induced in the winding 8 corresponds to the voltage set up across the primary winding so that the entire degeneratively back-coupled voltage e_1 corresponds to the sum of the voltage across the impedance Z and the voltage drop across the resistance R_0 which corresponds to the resistance 9. Again it is assumed, for simplicity, that $R_2 > |R_0 + Z_\pi|$. The voltage e_1 is then determined by the expression:

$$e_1 = e/R_2(R_0 + Z_\pi)$$

and is consequently proportional to the resultant impedance $Z_t = R_0 + Z_\pi$. This resultant impedance Z_t is indicated in the diagram shown in Fig. 9.

As stated above the impedance Z_π is constant and corresponds to R in a considerable portion of the transmission-range. Then the impedance Z_π increases to the cut-off frequency f_c while retaining, however, the character of a resistance. Consequently, the total impedance Z_t in the entire transmission-range is a resistance whose value is at first constant and then increases to the limiting frequency f_c . The degeneratively back-coupled voltage varies in a corresponding manner and is not subject to phase displacements in the transmission-range. With regard to the frequencies which are greater than the cut-off frequency, the impedance Z_π is capacitative. The value of this capacitative impedance decreases with the frequency. Hence, when the frequencies exceed the cut-off frequency the phase-angle of the total impedance Z_t abruptly varies by an angle ϕ which decreases with an increasing frequency. The phase-angle of the degeneratively back-coupled voltage varies in exactly the same manner. Owing to the presence of the resistance R_0 , which establishes the current feedback, the angle ϕ is always smaller than 90° ; consequently the phase angle of the degeneratively back-coupled voltage always remains smaller than 90° but decreases with an increasing frequency to thereby prevent the negative feedback from passing into a back-coupling.

Although I have described my invention with reference to specific examples and applications

I do not desire to be limited thereto because obvious modifications will present themselves to one skilled in this art.

What I claim is:

1. In an amplifier having an input circuit and an output circuit, means to obtain a degeneratively back-coupled voltage from the output circuit, an output transformer in said output circuit and provided with primary and secondary windings, current feedback means controlled by the current traversing said primary winding, and capacities connected in parallel with said windings, said capacities and the leakage inductance of the transformer forming a low-pass filter of the π type having a cut-off frequency corresponding at least to the highest frequency to be amplified.

2. In an amplifier having an input circuit and an output circuit, means to obtain a degeneratively back-coupled voltage from the output circuit, an output transformer in said output circuit having a one-to-one transformer ratio and being provided with a primary winding and a secondary winding, a capacity connected in parallel with the secondary winding, and a capacity 25

connected in parallel with the primary winding and having a value about twice the value of the first capacity, said capacities and the leakage inductance of the transformer forming a low-pass filter of the π type having a cut-off frequency corresponding at least to the highest frequency to be amplified.

3. In an amplifier having an input circuit and an output circuit, means to obtain a degeneratively back-coupled voltage from the output circuit, an output transformer in said output circuit and having a one-to-one transformer ratio and being provided with a primary winding and a secondary winding, current feed-back means controlled by the current traversing said primary winding, a capacity connected in parallel with the secondary winding, and a capacity connected in parallel with the primary winding and having a value about twice the value of the first capacity, 10 said capacities and the leakage inductance of the transformer forming a low-pass filter of the π type having a cut-off frequency corresponding at least to the highest frequency to be amplified.

WILLEM SIX.
